ROBERT C. HIGGINS, OF SOUTH BEND, INDIANA, ASSIGNOR TO MALLEABLE STEEL RANGE MANUFACTURING COMPANY, OF SOUTH BEND, INDIANA, A CORPORATION OF INDIANA.

KEROSENE-STOVE CONSTRUCTION.

Application filed April 20, 1925. Serial No. 24,363.

This invention relates to improvements in kerosene stoves and more particularly to a new and novel construction for a top plate for kerosene and other liquid hydrocarbon 5 burning stoves.

The object of the invention is to produce an improved stove top, especially adapted for stoves equipped with kerosene burners and calculated to afford more efficient and 10 uniform heat transmission and distribution to the cooking utensils placed thereon.

A further object of the invention is to provide an improved construction for a burner plate adapted to be placed directly 15 over the burner and so designed as to protect the burner from being extinguished and otherwise fouled by drippings from the utensils in which food is being cooked.

A preferred embodiment of the invention 20 is disclosed in the accompanying drawings in which:

Figure 1 is a perspective view of a portion of the stove;

Figure 2 is a view in vertical section 25 through the stove top and parts adjacent;

Figure 3 is an enlarged top plan view of a section of the stove top showing the burner plate.

Figure 4 is a section through the burner 30 plate taken on line 4, 4, of Figure 3, and.

Figure 5 is a view in bottom plan view of the burner plate.

As clearly shown in Figures 1 and 2, the 35 stove is generally of a design common to stoves of this character, but differing radically in the construction of the top plate, or heating surface, which in the usual gas or kerosene stove is an open grille extending over the burners. In the present construction the top of the stove consists of a solid 40 cast iron plate 1, of at least one quarter inch in thickness, with a polished top surface. This top plate may be either of a single piece or made up of two or more sections depending on the size of the stove. The top plate extends over the entire 45 surface of the stove and extends beyond the front and side edges thereof, terminating in a downwardly curved edge 1^a.

Beneath the top plate are located one, two 50 or more burners 2, designed to burn with an exceedingly hot blue flame, in the form of a ring of small jets issuing from the openings around the edge of a circular vaporizing member 3, at the top of the burner. 55

Immediately over each burner is a circular burner plate 4, considerably greater in diameter than the burner beneath it, and removably seating in circular openings in the top plate, with its upper surface flush therewith. The burner plate is also of a solid 60 cast iron construction, but as will presently be seen is something more than a mere circular section of the stove plate.

These plates are cast somewhat thinner 65 than the stove plate, except for a heavy rim 4^a extending around the periphery thereof. Immediately inward from the rim 4^a is a series of radial slots 5, extending through the plate and inwardly toward the center a 70 distance equal to about one half the radius of the plate, thus providing a solid or imperforate central portion approximately the same diameter as the burner top below it.

On the under surface of the plate, Figure 75 5 is a spider-like arrangement of ribs 6, radiating from the center and in alignment with the slots 5, beyond. These ribs taper slightly from the center outward, become less pronounced as they diverge. At the 80 inner ends of the slots 5 these ribs terminate abruptly in downwardly projecting nubs 7, tapering slightly to a rounded point.

The plate is designed in this way for several reasons, the most important being to 85 prevent the plate from warping or cracking under the rapid changes in temperature, and the high temperatures to which it is subjected. This accounts for the reduced thickness and the radial reinforcing 90 ribs on its under side. The outer ring of radial slots are also provided to permit the heat from the burner to pass through and come in contact with the bottom of the cooking utensil, although spaced a sufficient distance from the center to avoid direct contact of the flame therewith. In this way 95 the heat is more effectively utilized, by per-

mitting direct contact of the heat with the utensil beyond the zone immediately above the flame.

The purpose of the nubs or projections 7 at the junction of the ribs and slots is one especially desirable where burners of the open type are used, as a means for protecting the burner from being fouled or the flame extinguished by the contents of the 10 utensils boiling over and flowing through the slots in the plate and thence onto the burner. Thus the nubs provide barriers which effectually prevent the liquid from passing beyond them, but rather cause it to 15 drip from their ends, clear of the burner.

As already pointed out, the stove plate 4, seats flush in a circular opening in the top plate. For reasons presently to be pointed out, this seat is of a special construction consisting of a series of annularly arranged 20 lugs 8, formed integral with the top plate, and spaced apart at equal intervals about the opening. These lugs are depressed below the bottom surface of the top plate and 25 projecting inwardly, form an annular rack, supporting the burner plate around its rim. Between the lugs are a series of circumferential recesses or notches 9, likewise spaced apart at equal intervals and of about the 30 same length and breadth as the lugs. These notches form with the edges of the burner plate a series of slots which serve two purposes, first, they provide additional openings to permit the heat from the burner to 35 pass through in direct contact with the bottom of cooking utensil, and secondly, they serve to provide a series of air spaces between the burner plate and the surrounding top plate, thus decreasing the amount of 40 heat which is conducted from the burner plate to the top plate. The desirability of this provision is obvious, since it confines the heat to the burner plate, which ordinarily is about the size of the bottom of the cooking 45 utensil and further, it avoids the unnecessary heating of the top plate with the attendant dissipation and loss of the effective heat from the burner.

The combination therefore of a solid top 50 plate and solid burner plates, imperforate except for the slots, constitutes a practical and useful feature in kerosene stoves of the vapor or generating type, which burn with an exceedingly hot flame and therefore 55 much better results are obtained by spreading the heat throughout a larger area of uniform temperature rather than confining it to a relatively small area at a very high temperature directly above the burner. 60 This is especially true under ordinary conditions of cooking although it is obvious that where rapid heating is desired the burner plate may be removed, and the cooking or boiling carried on over the open flame.

The burner plate with provision for protecting the burner against drippings, and the method of supporting the flame so as to confine the heat to an area commensurate to the surface of the average cooking utensil, 70 but greater than the area in direct contact with the flame, is of great advantage in obtaining maximum heating efficient with economical fuel consumption.

I claim as my invention: 75

1. In a stove of the character described, the combination of a burner, a solid plate of cast metal extending over the top of the stove above said burner and comprising a burner plate having an imperforate portion located immediately above said burner, a series of radial slots extending from said imperforate portion toward the periphery of said burner plate, and a series of circumferentially spaced slots beyond said radial 80 slots.

2. In a stove of the character described, the combination of a solid plate of cast metal extending over the top of the stove and, provided with a circular opening, a 90 burner mounted beneath said opening, and a plate seating in said opening and having a central imperforate portion immediately above said burner, radially disposed slots extending from said imperforate portion 95 and circumferentially spaced slots extending about the margin thereof.

3. In a stove of the character described, the combination of a burner, a solid plate of cast metal extending over the top of the 100 stove above said burner and provided with an opening immediately above said burner having a series of circumferentially extending recesses around said opening, and a burner plate seating in said opening and 105 having an imperforate central portion substantially greater than said burner, and slots radiating from said central portion.

4. In a stove of the character described, the combination with a burner of a burner 110 plate having an imperforate central portion immediately above, and having a diameter substantially greater than said burner, a series of slots radiating from said central portion, and depending projectings formed 115 on the bottom surface of said plate at the inner ends of said slots.

5. In a stove of the character described, the combination with a burner of a burner plate above said burner and comprising an 120 imperforate central portion immediately above said burner, and a series of slots radiating from said central portion, there being formed on the bottom surface of said plate and at the inner end of each slot a depending nub spaced outwardly beyond the periphery of said burner.

6. In a stove of the character described, the combination with a top plate and a 125 burner of a burner plate above said burner 130

and comprising an imperforate central portion of substantially the diameter of said burner, and a series of radial slots surrounding said central portion, there being 5 formed on the bottom surface of said plate a series of ribs radiating from the center thereof, in alignment with said slots, and

terminating at the inner ends thereof in depending nubs, spaced outwardly beyond the periphery of said burner. 10

Signed at South Bend this 17 day of April 1925.

ROBERT C. HIGGINS.
